CENTRALIZED TRAFFIC CONTROL SYSTEM
FOR RAILROADSDarrol F. De Long, Rochester, N. Y., assignor to
General Railway Signal Company, Rochester,
N. Y.

Application August 7, 1930, Serial No. 473,529

25 Claims. (Cl. 246—3)

This invention relates to centralized traffic controlling systems for railroads, and more particularly pertains to a code type communication system, by means of which a dispatcher or operator may govern, from a conveniently located control office, the operation of a plurality of traffic controlling devices located along a railroad, and is informed of the progress of trains and the operated conditions of such traffic controlling devices.

It has been found expedient in governing the movements of trains over a railroad, to place the control of such train movements under the supervision of an operator stationed at a convenient point along the railroad. In order that this supervision may be the most efficient, it is desirable that an electric communication system be provided to enable the operator to manually control the signals, switches, derails, and the like located along the railroad, and also to inform the operator as to the progress of trains and such other conditions as may be desirable. In such a system, the various track switches and derails are usually operated by power, under the manual control of the operator, with suitable provisions for approach locking means local thereto preventing their improper and dangerous operation; and the signals governing traffic over the switches are automatically controlled by adjoining track circuits in accordance with automatic signalling practice, subject to the control of the operator, who may hold any such signal at stop irrespective of its automatic control, or may allow such signals to clear when the positions of trains are such as to make it safe to do so. The intermediate signals, which are between those signals at route determining points, are preferably provided only with automatic control governed in accordance with trackway conditions.

The present invention relates more particularly to such a communication system which is employed to enable the operator to condition at will, a function control relay, for each traffic controlling device in the territory under his supervision, in such a way that the signals, switches, derails, and the like may be moved to such positions as the operator may desire, subject to the automatic control of the signalling system associated therewith which prevents their unsafe operation. This function of the system is conveniently termed the transmission of controls.

The communication system, constituting more particularly the subject matter of this invention,

is further utilized to transmit to the operator the position of the various traffic controlling devices, the occupancy of certain track circuits and such other conditions as may be desirable to facilitate in the governing of train movements over the railroad. This function of the system is conveniently termed the transmission of indications.

By way of explanation, and without attempting to define the nature or scope of the invention, it may be stated, that in the communication system of this invention, certain adjacent or associated traffic controlling devices with their related indications are preferably grouped in what may be referred to as a field or way station. All such way stations, throughout the railroad, are connected with the control office by three line wires which are employed to form a stepping circuit and a message circuit.

In the transmission of controls from the control office, for the purpose of operating signals, switches, and the like at a particular way station, a series of stepping impulses are placed upon the stepping circuit extending to all the stations, which causes step-by-step means at the control office and at each of the way stations to take a plurality of steps. During a number of these steps taken by each step-by-step means, a combination of impulses, conveniently termed a code call, which is allotted to that station, is transmitted over the message circuit extending to all the way stations, but effective selecting response thereto is obtained only at the particular station being called. After such selection of that station, the remaining steps of the cycle are employed to transmit both the desired new controls and the indications of that station, as then set up, by impulses placed upon the message circuit by suitable control means respectively at the control office and that way station.

Indications of the position of switches, signals, and the like and the conditions of certain track circuits, are transmitted to the control office from the several stations one at a time. A station, having one or more new indications to transmit, initiates the system into operation causing a series of impulses to be placed upon the stepping circuit to operate the step-by-step means at the control office and at each way station. During a certain number of the steps taken by the step-by-step means, a combination of impulses is placed upon the message circuit, at that way station, corresponding to its code call which identifies or registers that station in the control office. After this station selection or registration has taken place, the remaining steps of that cycle of

operation are taken during which impulses are placed upon the message circuit in correspondence to the new indications to be transmitted from that station and in correspondence with 5 the controls for that station as then set up in the control office.

If more than one station is ready to send in new indications to the control office, these stations are allowed to register themselves and communicate their indications, one station at a time, in a sequence or order determined by their geographic location.

Since, in accordance with this invention, the transmission of new controls and the registration 15 of each station desiring to send in new indications is accomplished over the message circuit, an important feature of the system of this invention resides in the manner in which only one such station is selected for the transmission 20 of new controls and only one such station having new indications is allowed to register itself in the control office during a particular operating cycle, with only one of these functions occurring during a particular operating cycle of the system.

25 The communication system of this invention may be said, therefore, to be of the station selective type employing code combinations or code calls for station selection both for the transmission of controls and indications.

30 Various other characteristic features, functions and advantages of the system of this invention are more conveniently explained and pointed out hereinafter, following the description of one embodiment of the present invention and 35 its mode of operation. Many of these features and advantages will be apparent as the description progresses, and need not be specifically pointed out in detail.

For the purpose of explaining the nature of 40 the invention, there has been shown in the accompanying drawings, one typical embodiment of the invention adapted for controlling the switches and signals at the ends of passing sidings on a single track railroad; but the same principles 45 and functioning of the invention, and the same apparatus and circuits may be employed, or may be adapted by obvious modifications, for the control of switches, signals, derails or other traffic controlling devices for all kinds of track lay-outs, 50 and for the receiving of indications of the positions or conditions of such traffic controlling devices, track circuit occupancy and such other conditions as may be desirable.

In describing the invention in detail, reference will be made to the accompanying drawings, 55 in which similar parts throughout the several views are designated by like reference characters provided with distinctive exponents, and in which—

60 Figs. 1A and 1B when placed end to end illustrate the apparatus and circuits for the control office of a communication system constructed and arranged according to the present invention;

65 Figs. 2 and 3 illustrate the equipments for two typical way stations of the system, having distinctive code calls for their selection;

Fig. 4 shows the arrangement of the line circuits;

70 Fig. 5 shows a typical table of code combinations of impulses employed for station selection in the system.

For the purpose of simplifying the illustration and facilitating the explanation, the various parts and circuits constituting the system have 75 been shown diagrammatically and certain con-

ventional illustrations have been employed, the drawings having been made more with the idea of making it easy to understand the principles and mode of operation of the system, than with the idea of illustrating the specific construction 5 and arrangement of parts that would be employed in practice. Thus, the various relays and their contacts are illustrated in a conventional manner, and symbols are used to indicate connections to the terminals of batteries or other 10 sources of electric current in place of showing all the wiring connections to such terminals.

Considering first the general organization of the system, three line wires are employed in the particular form shown, namely, a stepping line, 15 a message line and a common return line. These line wires extend from the control office through the several stations, with the stepping line connected to the common return wire beyond the last way station (see Fig. 4), while the message 20 line is left open-ended at the last station. These line wires are employed to form two separate circuits, with a common return connection (common return line), conveniently termed a stepping circuit and a message circuit.

The stepping line wire includes at each station and at the control office, a polar line relay L (see Fig. 4); and the message line wire includes 30 at each station a back contact of a field control relay FC.

The stepping circuit and the message circuit are both supplied with direct current from sources located at the control office. The field stations do not supply current to the line circuits of the system at any time. This supply of direct current in the control office for energizing the stepping and message circuits may be a storage battery with suitable trickle charge or other charging means, motor generator, or any other suitable source, the voltage required varying with 40 the number of way stations and the length of the line circuits connecting such way stations with the control office.

A source of direct current is required for each 45 field station for energizing the local circuits of the communication system, and for operating the signals, switches and the like at that station. Storage batteries, maintained charged through rectifiers from a suitable power line, are preferably employed for this purpose in accordance 50 with common practice.

Such sources of electrical energy which supply 55 current to the circuits local to the control office and each of the way stations are represented by the use of the conventional battery symbols (+) and (−) indicating connections to the opposite terminals of a battery or other suitable source of direct current; and the current, in the circuits with which these symbols are used, always flows 60 in the same direction when the respective circuits are closed. The source of current supply for the line circuits is represented by a battery BT having a center tap connected to the common return line (see Fig. 1B). This battery has its positive and negative terminals designated by 65 symbols (B+) and (B−), which are used to designate the connections of various circuits thereto throughout Figs. 1A and 1B to simplify the circuits of the control office. It will be noted that where a circuit is indicated as connected to terminals (B+) and (B−) the current flow in such 70 circuits may be reversed in accordance with the conditions to be met, as provided for by the system of the present invention.

The operations of this communication system 75

are preferably performed by relays of the tractive armature type. Certain of these relays, such as the line relays L, are of the three-position polarized type, the movable armature being biased to assume an intermediate or neutral position when the relay winding is deenergized. When such polar relay is energized, the armature assumes one or the other of two opposite extreme positions in accordance with the direction of current flow in its winding. The contacts for these relays have been shown conventionally, and for convenience it is assumed that the contact fingers assume right hand extreme positions by the application of positive current and assume left hand extreme positions by the application of negative current. Some of these relays are of the two position polar type, similar to the three-position polar type relay with the omission of the means biasing their contacts to intermediate deenergized positions. The contacts of these two-position polar type relays remain in the position to which they are last energized even after their windings are subsequently deenergized. The contact fingers for these two-position relays are similarly shown in a conventional manner, and are assumed to be moved to right-hand extreme positions by the application of positive current, and to left-hand extreme positions by the application of negative current.

All other relays are of the neutral type, shown conventionally, and are preferably of the type employed in telephone practice. Certain of these relays require two windings in accordance with their use in the circuits, and certain others require slow releasing characteristics which are obtained in the usual manner by the use of short circuited windings associated therewith. All of these relays are constructed according to the usual engineering practice having suitable characteristics for their various uses as employed in the circuits according to the present invention, quick operation of all relays being desirable except in the case of those relays having slow acting characteristics as conventionally illustrated by heavy base lines on such relays.

The control office equipment.—The equipment for the control office includes in general a suitable control machine provided with manually operable levers, a track diagram, indicating lamps and the like, so as to enable the operator by simple manipulation to control the signals, switches and the other traffic controlling devices of the system at the various way stations, and also have before him information of the response of such traffic controlling devices, and of the occupancy of various track sections, such as will enable him to handle the traffic over the system to the best advantage.

No attempt has been made to illustrate the construction of the control machine or the arrangement of parts preferably employed; but the manually operable control levers, the track diagram, indicating lamps, various relays and electrical connections have been diagrammatically illustrated to explain the function and operation of such system constructed according to the present invention, regardless of its particular application in practice.

In the control office (see Fig. 1A) two manually operable levers SGL and SML are respectively provided for operating the signals and the switch at the west end of a passing siding represented in the control office by a miniature passing siding on a track diagram. The lever SGL is of the three-position type having contacts 10 and 11

which make contact with their respective fixed contacts when in one of three positions; while the lever SML is of the two-position type having a movable contact 12 which makes contact with its respective fixed contacts when in extreme positions only. These levers are representative of all the manually operable levers on the control machine employed for the control of various traffic controlling devices in the field, each such lever being provided with what is termed a momentary contact, in this case contacts 13 and 14 for levers SGL and SML respectively, for momentarily closing a circuit as these levers are moved from any one of their positions to another.

The miniature track diagram, corresponding to the actual track lay-out in the territory under the supervision of the operator, is preferably made a part of the control machine positioned adjacent to the control levers for each of the several field stations. As representative of such a track diagram, the passing siding s is intended to represent an actual passing siding S in the field, such as shown in Fig. 2 of the accompanying drawings, and is located over its associated control levers SGL and SML.

Directly above the west end of this miniature passing siding s is located an indicator lamp I, which, when lighted, indicates the occupied condition of a detector track section at the corresponding end of the passing siding S in the field. This lamp is controlled by an indication storing relay IS. It is to be understood that various other indicator lamps, or other means, can easily be employed to indicate the position of the switches, the condition of the signals and other similar conditions, such means being controlled in a similar manner, as shown for the indicator lamp I.

Associated with each station is a storing relay SR, which is controlled by the momentary contact on each of the control levers included for that station. In other words, these storing relays register the operation of a control lever of the corresponding way station and remain energized until the new control set up by such movement of the control lever has been transmitted.

Each of the storing relays SR has a corresponding code determining or selecting relay CD. These code determining relays CD are energized by their respective storing relays SR and are arranged in a bank having their circuits so interlocked with the storing relays SR that only one code may be superimposed upon the message circuit during any particular cycle of operation of the system. The particular one of these code determining relays CD, which is superior to the others, when energized, conditions the system for operation to cause the transmission of a code call characteristic of its corresponding station, in a manner more fully explained hereinafter.

Associated with each of the way stations is a message channel stepping relay bank, two such banks being shown in Fig. 1A for the respective way stations shown in Figs. 2 and 3.

The control office equipment includes a code channel stepping relay bank having associated therewith a group of code responsive relays. When the system is set into operation the relays 70 of the code channel stepping relay bank operate sequentially closing code channels for the respective code responsive relays, which respond to the code being received or being sent in a manner to transfer the stepping operation from 75

the code channel stepping relay bank at the end of the last code step to the particular message channel stepping relay bank corresponding to the code call characteristic received by the code responsive relays. The relays of the selected message channel stepping relay bank then sequentially step through to the last message channel step at which time the system returns to its normal at rest condition, if there are no more new controls to be transmitted or new indications to be received.

Thus, the control machine in the control office for each field station includes two levers SGL, SML, a portion of track diagram with its indicating lamps, a storing relay SR, a code determining relay CD, a plurality of indication storing relays IS, and a message channel stepping relay bank.

The stepping relay banks count off the steps during each operating cycle of the system, relays preferably being employed for this purpose, but any other step-by-step mechanism could be used. In the arrangement shown providing for three station selecting or code steps (capable of selecting eight stations) and four control and indication steps, there are five stepping relays in the code channel stepping relay bank, namely, relays 1⁰, 2⁰, 3⁰, 4⁰, and a last code step relay LC⁰; and there are five stepping relays in each of the message channel stepping relay banks, namely, relays 5⁰, 6⁰, 7⁰, 8⁰, and a last message channel stepping relay LM⁰ (for way station No. 1). It should be understood that this is only one arrangement and that the number of steps would be determined in accordance with the number of stations in use and the number of control and indication steps required for the various individual way stations.

The group of code responsive relays includes relays a, b and c, which are energized or left deenergized by their respective code channels. These code channels are set up by the code channel stepping relay bank.

The control office equipment also includes suitable means for applying impulses of positive and negative polarity alternately, at time spaced intervals, to the stepping circuit. While a motor driven commutator or equivalent means might be employed, two impulsing relays IR¹ and IR² are used, each of these relays having slow acting characteristics in accordance with the time period desired to be marked off.

The control office equipment further includes a line relay L⁰, a slow acting relay SL⁰, a cycle controlling relay CC, a starting relay S, a local starting relay LS, a field starting relay FS, and a field control relay fc.

The relays of the control office are interconnected by various controlling circuits, buses, jumpers, and the like which will be discussed more in detail during the description of the operation of the system.

Field station equipment.—With reference to Fig. 2 of the accompanying drawings, the signals 1—1A and 2—2A with the track switch TS at the west end of a passing siding S are shown as merely illustrative or representative of the traffic controlling devices which may be controlled and from which indications may be received as one field station.

70 The switch points TS are operated by a suitable switch machine SM, such for example as disclosed in the patent to W. K. Howe, No. 1,466,903 dated September 4, 1923, which is supplied with operating current from a local battery and which is preferably equipped with a dual

control selector permitting hand operation of the switch points as disclosed in the patent to W. K. Howe, Patent No. 1,852,573, dated April 5, 1932. The operation of this switch machine SM is controlled by a function control relay SMR of the two position polar type, the energization of this relay being under the control of the operator through the agency of the communication system of the present invention. The operation of the switch machine SM is also governed by suitable approach and release locking means (not shown) such as disclosed for example in the application of W. W. Wenholz et al., Ser. No. 409,103, filed November 22, 1929, so that irrespective of the operation of the switch machine function control relay SMR the switch points TS may not be improperly operated.

Train movements over the switch TS are governed by the signals 1—1A and 2—2A which are controlled by the condition of the associated track circuits, the position of the switch points, and in accordance with the position of the function relays DR and SGR, which are under the control of the operator for respectively determining in what direction traffic shall be established and whether or not the signals shall indicate clear for that direction. The circuits for controlling these signals in accordance with track conditions and the position of the switch points are not shown, but may be of the type shown and described for example in the application of S. N. Wight, Ser. No. 120,423, filed July 3, 1926.

A detector track section TK is associated with the track switch TS and is provided with the usual track battery 15 and track relay T to indicate the condition of occupancy of this track section.

According to the present invention, the communication system equipment for each field station includes the same arrangement of relays and the same circuits connecting the relays except in the case of certain jumpers or connections which may be rearranged or set to fit the particular code call characteristic of the station at which the equipment is located. These relays included within the communication part of the system of the present invention, are preferably housed in a portable cabinet or the like, so that they may be quickly detached in case of trouble to allow a new station unit to replace the old one. The similarity between the various way station equipments is illustrated by the fact that the same reference characters have been applied to both Figs. 2 and 3 with similar parts having distinctive exponents, the only difference between these stations being the positions of certain jumpers which feature will be more specifically described hereinafter.

The field station equipment includes a line relay L; a slow acting relay SL; a change relay CH; a field control relay FC; a code channel stepping relay bank having relays 1, 2, 3, 4, and a last code step relay LC; a message channel stepping relay bank having relays 5, 6, 7 and 8; a group of code responsive relays including relays A, B, C, and a code responsive control relay CR. It is to be understood that the number of stepping relays is merely illustrative and will vary according to practice in accordance with the number of stations and the number of indications and controls desired to be transmitted.

The change relay CH is provided to be energized momentarily each time the detector track relay T drops or picks up; but it should be understood that the change relay may depend upon

a change in position or condition of the signals, track switch, or other track circuits in a similar manner so that various other indications, when provided, may be transmitted to the control office. 5 The field control relay FC is energized when a particular field station initiates the system into operation. This field control relay has two functions, the first of which is to condition that station in a manner so that it may dictate the im- 10 pulses placed upon the code or station selecting steps of the operating cycle to accomplish its own selection and its registration in the control office; and second, to open the message line to subsequent way stations preventing interference from 15 any other station which may be similarly conditioned at that time and endeavoring to send in indications.

With this explanation of the equipment and general organization of the system, it is believed 20 that the nature, the various characteristic features and functions of the system will be best understood by further description being given from the standpoint of operation.

Operation of the system

25 It is believed desirable to briefly outline the operation of the system in a general way before discussing the various detailed steps therein and some of the combinations of conditions which 30 can arise in practice.

The system is normally at rest with the stepping circuit, including the stepping line and the common return line, deenergized, and with the message line having energy applied to it at the 35 control office although no circuit is completed at this time.

During the time that the system is at rest or in a period of blank, it may be initiated into operation from the control office or any one of the 40 several way stations. When thus initiated into operation, the system operates through a pre-determined number of steps comprising an operating cycle, after which the system returns to its normal or at rest condition in readiness for 45 the next initiation.

The means for impulsing the stepping circuit is located in the control office, so that the system may be initiated at the control office directly by starting this impulsing means; but when the 50 system is initiated from a way station, the message line, which is normally open-ended, is connected by the change relay to the common return line at the particular station having new indications to transmit, which causes current to 55 flow in a message circuit so as to initiate the impulsing means.

Each operating cycle includes the selection of a particular way station; the transmission of controls for that station as set up by the corresponding control levers in the control office; and the transmission of indications for that station as set up by the position of the traffic controlling devices located at that station.

If the system is initiated from the control office, every station is subsequently conditioned to receive code call impulses, and the particular station having a code call corresponding to the impulses which are transmitted from the control office is then selected so that the controls and indications associated with that station may also be transmitted. This functioning of the system is conveniently termed out-going station selection. 70

If the system is initiated from a way station, 75 such initiation conditions that station in such

a manner that subsequent thereto a combination of impulses corresponding to the code call of that station is transmitted by that station, thereby selecting that station and registering it in the control office, so that the controls and indications associated with that station may also be transmitted. This functioning of the system is conveniently termed in-coming station selection. 5

Thus, each cycle of operation may be said to include five parts, namely, initiation into operation, conditioning for out-going or in-coming station selection, station selection by the transmission of code impulses, transmission of control impulses, and the transmission of indication impulses. 10

The transmission of control and indication impulses occurs during each operating cycle. If the system is initiated from the control office, the control impulses included in the resulting cycle of operation are new controls, while the indication impulses included within that cycle are repeated as formerly transmitted; but if the system is initiated from a way station, the indication impulses included in the resulting cycle of operation are new indications, while the control impulses included within that cycle are repeated as formerly transmitted. This repetition of controls and indications serves to check each way station each time it is selected. 15

Thus, the description of the operation of the 20 system of the present invention conveniently divides itself into two sections, namely, a description of the transmission of new controls or out-going station selection, and a description of the transmission of new indications or in-coming station selection. Following the description of these 25 two functions of the system, their interrelation and co-action will be explained.

Outgoing station selection.—With the system at rest or in the period of blank, the operator 30 may accomplish the control of any traffic controlling device over which he has supervision, by moving the corresponding control lever to a suitable controlling position. This operation of a control lever from a former position to a new 35 position is registered or stored by a storing relay SR which in turn energizes a code determining relay CD, a local starting relay LS, a starting relay S and a cycle controlling relay CC. The system then operates through a cycle, due to a 40 predetermined number of impulses placed upon the stepping circuit. 45

This energization of the storing relay SR corresponding to the way station with which the control lever is associated, and the energization 50 of the corresponding code determining relay CD, determines that the resulting cycle of operation shall be one for out-going station selection, 55 which may be best explained by considering the detail operations involved. 60

For convenience let us assume that the operator desires to operate the track switch TS at the first way station (see Fig. 2) from a normal extreme position to a reverse extreme position so that traffic may be routed from the main 65 track onto the passing siding S, or vice versa, in accordance with subsequent control of the governing signals.

Manual starting.—To operate the track switch TS, the operator moves the contacts of the control lever SML to their extreme upper positions, and in so doing momentarily closes the contact 14 thereby energizing the storing relay SR¹ through a circuit from (+), through momentary contact 14, wires 17, 18 and 19, winding of relay 70 75

SR¹, to (—). Immediately, when the contacts of the relay SR¹ assume energized positions, a stick circuit for this relay is completed from (+), through back contact 20 of relay CD¹, wire 21, front contact 22 of relay SR¹, wires 23 and 19, winding of relay SR¹, to (—).

The energization of the relay SR¹ closes an energizing circuit for the code determining relay CD¹ from (+), back contact 30 of relay SL⁰, wire 31, front contact 32 of relay SR¹, wires 33 and 34, winding of relay CD¹, wire 35, back contact 36 of relay LM⁰, to (—).

When the contacts of the code determining relay CD¹ assume energized positions, this relay completes its own stick circuit from (+), through back contact 37 of relay LM⁰, wires 38 and 39, front contact 40 of relay CD¹, wires 41 and 34, winding of relay CD¹, wire 35, back contact 36 of relay LM⁰, to (—). Also, at this time, the stick circuit of the relay SR¹ is transferred from back contact 20 of relay CD¹, through front contact 20 of relay CD¹ to the control of back contact 37 of relay LM⁰, which circuit is now traced from (+), through back contact 37 of relay LM⁰, wires 38 and 42, front contact 20 of relay CD¹, wire 21, front contact 22 of relay SR¹, wires 23 and 19, winding of relay SR¹, to (—). In this connection it is noted, that the contact 20 of relay CD¹ is preferably of the make-before-break type, that is, a circuit from the heel of this contact through its back point is not opened until a circuit from the heel of this contact through its front point is completed, and vice versa, thus maintaining the stick circuit of the relay SR¹ closed during the actuation of the relay CD¹.

At the same time that the code determining relay CD¹ is energized, the local starting relay LS is energized through a circuit from (+), through front contact 45 of relay SR¹, wires 46 and 47, upper winding of relay LS, to (—). Immediately upon the energization of the relay LS its stick circuit is closed from (+), through back contact 50 of relay LM¹⁰, wire 51, back contact 52 of relay LM⁰, wires 53 and 54, front contact 55 of relay LS, lower winding of relay LS, to (—). The energization of the local starting relay LS closes the energizing circuit for the starting relay S from (+), through back contact 58 of relay SL⁰, wire 59, front contact 60 of relay LS, wire 61, winding of relay S, to (—).

The energization of the starting relay S closes the pick-up circuit for the cycle controlling relay CC from (+), front contact 62 of relay S, wires 63 and 64, winding of relay CC, to (—). This cycle controlling relay CC is then stuck up through a stick circuit from (+), through back contact 50 of relay LM¹⁰, wire 51, back contact 52 of relay LM⁰, wires 53 and 65, front contact 66 of relay CC, wires 67 and 64, winding of relay CC, to (—).

Energization of the cycle controlling relay CC closes its front contact 70, thereby conditioning the stepping line circuit in readiness for receiving impulses of alternate polarity to operate the step-by-step means located at the control office and at each of the way stations.

The relay CC also closes an energizing circuit for the relay IR¹ from (+), through front contact 71 of relay CC, wire 72, back contacts 73, 74, 75 and 76 of relays 10, 20, 30, 40 respectively, wire 77, back contacts 78, 79, 80, 81 and 82 of relays 50, 60, 70, 80 and LM⁰ respectively, wire 83, back contacts 84, 85, 86, 87 and 88 of relay 510, 610, 710, 810 and LM¹⁰ respectively, through similar contacts of the message channel stepping relay

banks corresponding to the other stations of the system, through the bus wire 90, back contact 95 of relay IR², winding of relay IR¹, to (—).

The energization of the relay IR¹ causes positive potential to be applied to the stepping line circuit from the positive terminal of the battery BT indicated as (B+), through back contact 96 of relay IR², front contact 97 of relay IR¹, wires 98 and 99, front contact 70 of relay CC, wire 100, winding of relay L⁰, through the stepping line to the several stations including therein the line relays L at each of those stations, to the common return line at the last station, thence to the mid-point of battery BT (see Fig. 4).

The energization of the stepping circuit causes the step-by-step means (shown as relays) at the control office and at each of the way stations to take one step, as hereinafter pointed out. This energization of the first stepping relay at the control office and at each way station occurs during the interval of time existing between the actuation of the polar contact of the line relay L⁰ to its right-hand energized position and the response of the contacts of the slow acting relay SL⁰ thereto.

In the control office, the energization of the first stepping relay opens the formerly traced energizing circuit of relay IR¹ at back contact 73 of relay 10, which would then cause the relay IR¹ to be deenergized and as soon as the contacts of this first stepping relay assumed energized positions, thus causing the first positive impulse on the stepping circuit to be of insufficient duration to energize the relays SL.

But, the relay IR¹ is maintained energized until the relay SL⁰ has assumed an energized position, due to a holding circuit including a front contact of relay 10 and a front contact of the starting relay S. This circuit may be traced from (+), through a front contact 71 of relay CC, wire 72, front contact 73 of relay 10, wire 101, front contact 102 of relay S, wire 103 to bus 90, back contact 95 of relay IR², winding of relay IR¹, to (—). When the relay SL⁰ is energized, the relay S is deenergized at back contact 58, thereby breaking the holding circuit of the relay IR¹ at front contact 102 of relay S and completing the energizing circuit for the relay IR² from (+), front contact 71 of relay CC, wire 72, front contact 73 of relay 10, wire 101, back contact 102 of relay S, wire 104 to bus 91, back contact 105 of relay IR¹, winding of relay IR², to (—).

The energization of the relay IR² causes negative potential to be applied to the stepping circuit from the negative terminal of the battery BT indicated as (B—), through front contact 107 of relay IR², back contact 108 of relay IR¹, wires 109 and 99, front contact 70 of relay CC, wire 100, winding of line relay L⁰, through the stepping circuit as heretofore traced to the mid-point of battery BT.

The energization of the stepping circuit with negative potential causes the polar contacts of the line relays L to be operated to left hand positions, causing the step-by-step means at the control office and at each of the way stations to take the second step.

The energization of the second stepping relay 20 in the control office deenergizes the stepping relay 10 thereby opening the energizing circuit of the relay IR² at front contact 73 of relay 10. As soon as the relay IR² is deenergized, which is an appreciable length of time after the deenergization of the relay 10, the bus 90 is energized through front contact 74 of relay 20 thereby en-

ergizing the relay IR¹. This again places positive potential upon the stepping circuit causing the step-by-step means at the control office and at each of the way stations to take the third step.

5 In a similar manner as the relays 1⁰ and 2⁰ have alternately energized the buses 90 and 91, likewise the subsequent stepping relays, such as relays 3⁰, 4⁰, 5⁰, 6⁰, 7⁰, 8⁰ and LM⁰ cause these buses 90 and 91 to be alternately energized, resulting in the 10 alternate energization of the relays IR¹ and IR² respectively, to place impulses of alternate polarities upon the stepping circuit. When the last 15 message channel stepping relay LM, such for example as LM⁰ is energized, the stick circuit for the relay CC is opened at the respective back contact (in this case back contact 52) thereby deenergizing it, which in turn removes the current supply for the impulsive relays IR at front contact 71 of relay CC, causing the impulsive 20 contact of the stepping circuit to cease.

25 As we have now considered the manner in which the stepping circuit may receive impulses of alternate polarity, we shall now consider the manner in which the application of these impulses to the stepping circuit causes the step-by-step means at the control office and at each way station to sequentially and synchronously operate.

30 *Step-by-step operation.*—From the above description, it can be seen that the manual starting of the system causes the application of the first impulse to the stepping circuit, while the response of the step-by-step means in the control office causes the application of the second impulse. Hence, the impulsive of the stepping circuit and the operation of the step-by-step means are interdependent.

35 However, for convenience let us consider that the manual starting causes the first impulse to which the step-by-step means responds, thus causing the second impulse, and so on as above explained, in order to observe how the step-by-step means at the central office and at each way station responds to such impulses.

40 45 For convenience, the code channel stepping relay bank at the first way station (see Fig. 2) will be more specifically considered in pointing out the operation of the stepping relay banks, although it is to be understood that the operation of every stepping relay bank is identical and may be readily understood by analogy.

50 With the first impulse of positive polarity placed upon the stepping circuit, the contacts of the line relay L are energized to right-hand extreme positions energizing the relay SL from (+), through contact 110 of relay L in a right-hand position, wire 111, winding of relay SL, to (-). As this first impulse is of relatively long duration in respect to the following impulses the 55 slow acting relay SL receives current for a sufficient period of time to actuate its contacts to energized positions.

55 During the time that the line relay L is energized and the contacts of the relay SL have not yet responded, a pick-up circuit for the relay 1 is closed from (+), through contact 115 of relay L in a right-hand position, wire 116, back contact 117 of relay SL, lower winding of stepping relay 1, wires 118 and 119, back contact 60 65 70 75 120 of stepping relay 2, to (-). This pick-up circuit for the relay 1 is closed until the contacts of the relay SL assume energized positions at which time its stick circuit is closed from (+), front contact 121 of the relay SL, wires 122 and front contact 123, front contact 124 of stepping relay 1, upper

winding of stepping relay 1, wires 125 and 119, back contact 120 of stepping relay 2, to (-). It is noted in this connection, that the front contact 121 is to be preferably closed before the back contact 117 is opened.

75 80 85 90 95 100 105 110 115 120 125 130 135 140 145 150 When the relay SL becomes energized with the stepping relay 1 energized, a circuit is completed from (+), through contact 115 of relay L in a right-hand position, wire 116, front contact 117 of relay SL, wire 126, front contact 127 of relay 1, lower winding of relay 2, wires 128 and 129, back contact 130 of relay 3, wires 131, 132 and 122, front contact 121 of relay SL, to (+). It is obvious that both ends of this circuit are connected to the same terminal of the source thereby leaving the stepping relay 2 unaffected.

150 155 160 165 170 175 180 185 190 195 200 205 210 215 220 225 230 235 240 245 250 255 260 265 270 275 280 285 290 295 300 However, upon the energization of the line relay L with the opposite polarity in response to the next impulse on the stepping circuit following an intervening period of deenergization, negative potential is connected to this circuit through contact 115 of relay L in a left-hand position. This effectively energizes the stepping relay 2, opening the stick circuit for the stepping relay 1 at back contact 120 and closing its own stick circuit through front contact 120. This stick circuit for the relay 2 is traced from (+), through front contact 121 of relay SL, wires 122, 132 and 131, back contact 130 of relay 3, wires 129 and 133, upper winding of stepping relay 2, front contact 120 of stepping relay 2, to (-).

ing stepping relay, and the deenergizing time of the corresponding impulsing relay IR, while the time interval between successive impulses includes the pick-up time of the corresponding relay IR. During the energization of the line relays L, the proper stepping relay for that impulse is energized and remains energized until the next step is taken so that during the time of deenergization of the line relays marking off the execution period, sufficient time may be allowed by the pick-up time of each one of the impulsing relays IR to insure the operation of the relays controlled over the channel circuits.

Conditioning of field stations for the reception of code calls.—The control office and each way station is provided with a group of code responsive relays which are controlled through their respective channel circuits. In order that the proper station may be selected or chosen from among all of the stations, the corresponding code responsive relays at the control office and at each station must be connected in multiple between the message line and the common return line on corresponding steps, but as such a multiple connection of the code responsive relays is undesirable at the way stations during an in-coming station selecting cycle of operation, each way station must be conditioned at the beginning of an out-going station selecting cycle in order that its code responsive relays will be effectively governed by the code impulses placed upon their respective channel circuits.

This conditioning of each station for the reception of code impulses or code calls at the beginning of an out-going station selecting cycle, is accomplished on the first channel circuit completed when the first stepping relay at the control office and at each of the way stations is energized. If this channel circuit is energized then every station is conditioned for the reception of code calls; while, if this first channel circuit is not energized, no station is conditioned for the reception of code calls.

As the system for this operating cycle under consideration has been initiated from the control office, the field control relay *fc* at the control office is deenergized, this deenergization causes this first conditioning channel circuit to be energized.

50 In other words, the system has been manually started or initiated into operation from the control office resulting in the energization of the first stepping relay at the control office and at each of the way stations, upon which step a channel circuit is completed during the execution period of the step, that is, with relays IR¹ and IR² deenergized, from the positive terminal of the battery BT indicated as (B+), through back contact 140 of relay *fc*, wire 141, front contact 142 of relay 1⁰, wire 143, back contact 144 of relay IR¹, wire 145, back contact 146 of relay IR², wire 147, front contact 148 of relay SL⁰, through the message line to every way station (at the first way station for example), through wire 150, front contact 151 of relay SL, wire 152, front contact 153 of stepping relay 1, wire 154, lower winding of relay CR, wires 155, 156, 157 and 158, to the common return line, and thence to the mid tap of the battery BT. A similar circuit at each way station from the message line through its corresponding code response controlling relay CR is completed to the common return line. Thus, the energization of this channel circuit accomplishes the energization of the 75 relays CR at each of the way stations in multiple,

thereby conditioning every station for the reception of code calls as determined in the control office.

The code response controlling relay CR is maintained energized throughout the cycle of operation by a stick circuit completed from (+), through front contact 121 of relay SL, wires 122, 132, 134, 135, 136, 137, 138 and 139, upper winding of relay CR, front contact 149 of relay CR, to (—). A similar circuit is completed for the respective code response controlling relay CR at each of the other stations.

Transmission and reception of code calls.—As the relay CR at each of the way stations is energized, the code responsive relays at the way stations are connected in multiple across the message line and the common return line through their respective channel circuits. Although any number of stepping relays could be employed having a corresponding number of code responsive relays, only the stepping relays 2, 3 and 4 have been shown as having code responsive relays A, B and C respectively. It is evident that each of these code responsive relays A, B and C, may be energized or left deenergized on its respective step, thus providing eight combinations which may be assumed by the contacts of these relays by suitably arranging their energizing impulses. These eight combinations have been represented by symbols in a Typical table of codes (see Fig. 5), a "+" symbol representing the energized condition of the corresponding relay or a "-" symbol representing the deenergized condition of that relay.

With reference to the Typical table of codes (see Fig. 5), a code call requiring the three code responsive relays A, B and C to be energized is represented by code call No. 1 and further denotes that the channel circuits for these three code responsive relays should each be energized in order to select the station having that code call assigned to it. Similarly, the code call No. 7, for example, indicates that the respective channel circuits for the code responsive relays A, B and C should be deenergized, deenergized and energized in order to select the station having that code call characteristic.

For this particular cycle of operation under consideration, the control lever SML in the control office has been operated resulting in the energization of the code determining relay CD¹ which must provide energization of proper code channel circuits to select the first way station (see Fig. 2). This first way station has been assigned arbitrarily the code combination or code call symbolically represented in the Typical table of codes (see Fig. 5) by code call No. 3, which requires that the first and third code channel circuits shall be energized to energize relays A and C. In accordance with this, code jumpers 160 and 162 have been provided so that when the code determining relay CD¹ is energized, the first and third code channels (closed when stepping relays 2 and 4 are energized and the stepping line is deenergized) may be energized.

Considering that the stepping relay 2⁰ in the control office and the stepping relay 2 at each of the way stations are energized, then during the execution period of that step, a code channel is completed for energizing the code responsive relay *a* in the control office and the corresponding code responsive relay A at each of the way stations from the positive terminal of the battery BT indicated as (B+), through code jumper 160, front contact 163 of relay CD¹, wire 75

164, back contact 165 of relay *fc*, wire 166, lower winding of relay *a*, wire 167, front contact 168 of stepping relay 2⁰, back contact 142 of stepping relay 1⁰, wire 143, back contact 144 of relay IR¹, wire 145, back contact 146 of relay IR², wire 147, front contact 148 of relay SL⁰, through the message line to each of the way stations, (at the first way station for example) through wire 150, front contact 151 of relay SL, wire 152, back contact 153 of stepping relay 1, front contact 169 of stepping relay 2, wire 170, lower winding of relay *A*, code jumper 180, to the code bus 260, back contact 171 of relay FC, code bus 201, front contact 172 of code response controlling relay CR, wires 173, 156, 157 and 158, to the common return line, and thence to the mid point of the battery BT. Similarly, the relays A¹, A², etc., at the second, third and remaining way stations respectively are energized during this closure of the first code channel circuit, it being understood of course that these relays *A* at each station are in multiple across the message line and the common return line.

The code responsive relay *A* is maintained energized throughout that cycle of operation by a stick circuit closed from (+), through front contact 121 of relay SL, wires 122, 132, 134, 135, 136, 137, 138 and 212, upper winding of relay *A*, front contact 213 of relay *A*, to (-). This stick circuit is representative of the stick circuit completed by each of the code responsive relays when energized, the respective stick circuits being completed by the corresponding SL relay energized until the end of the particular cycle of operation.

35 During the execution period of the next step (third), the code channel circuit for that step is not energized due to the omission of a suitable code jumper in the control office (see Fig. 1A), similar to code jumper 160 provided in the case 40 of the first code channel circuit. Thus, the code responsive relay *b* in the control office and the code responsive relays *B* at each of the way stations, remain deenergized.

During the execution period of the next step 45 (fourth), the code channel circuit for that step is energized from the positive terminal of the battery BT indicated as (B+), through jumper 162, front contact 174 of relay CD¹, wire 175, back contact 176 of relay *fc*, wire 177, lower winding of code responsive relay *c*, wire 178, front contact 179 of stepping relay 4⁰, back contacts 185, 168 and 142 of relays 3⁰, 2⁰ and 1⁰ respectively wire 143, back contact 144 of relay IR¹, wire 145, back contact 146 of relay IR², wire 147, front contact 148 of relay SL⁰, through the message line to each of the way stations (at the first way station), for example, through wire 150, front contact 151 of relay SL, wire 152, back contacts 153, 169 and 186 of relays 1, 2 and 3 respectively, front contact 187 of stepping relay 4, wire 188, lower winding of code responsive relay *C*, code jumper 182, code bus 200, back contact 171 of relay FC, code bus 201, front contact 172 of code response controlling relay CR, wires 173, 156, 157 and 158, to the common return line, and thence to the mid-point of the battery BT. Similarly, the code responsive relays *C* at each of the way stations are energized as they are connected in multiple across the message and common return lines.

In a similar manner a larger number of code responsive relays could be employed but for the purpose of a disclosure of the present invention only three such relays have been shown.

75 At the first way station (see Fig. 2), a circuit

is completed through contacts on the respective relays A, B and C and a chain of connecting code jumpers, so that the step-by-step operation is transferred from the code channel stepping relay bank to the message channel stepping relay bank at that station. At the second way station and at all other way stations, the contacts on the relays A, B and C and the chain of connecting code jumpers at those stations do not complete a circuit for transferring the stepping operation to the message channel stepping relay banks at those stations.

On the fifth impulse of the stepping circuit, the last code channel stepping relay LC at every station is energized and locks up the stepping operation at all of the stations except the first (see Fig. 2), where the stepping relay 5 is energized in multiple with the last code channel stepping relay LC at that station.

This pick-up circuit for the stepping relay 5 is closed from (+), through polar contact 115 of line relay L in its right hand position, wire 116, front contact 117 of relay SL, wire 126, back contacts 127, 190 and 191 of relays 1, 2 and 3 respectively, front contact 192 of stepping relay 4, wires 193 and 194, front contact 195 of code responsive relay *A*, code jumper 205, back contact 196 of code responsive relay *B*, code jumper 206, front contact 197 of code responsive relay *C*, code jumper 207, wire 198, lower winding of stepping relay 5, wires 199 and 210, back contact 211 of stepping relay 6, to (-). These message channel stepping relays 5, 6, 7 and 8 are sequentially energized upon the application of the corresponding impulses upon the stepping circuit.

As the step-by-step operation at a particular selected station must be transferred from the code channel stepping relay bank to the message channel stepping relay bank, when the code responsive relays assume positions corresponding to the code call assigned to that station, then the chain circuit through the front or back contacts of the code responsive relays must be completed when these relays assume the positions corresponding to the code call. Thus, it is obvious that the code jumpers 205, 206 and 207 at each station must be positioned to connect with the front or back contact of their respective code responsive relay in accordance with the code call of that station. For example, the jumper 205 should be connected to the front contact of the code responsive relay *A* at each station having a code call designated by the symbol "+", while it should be connected to the back contact of that relay at each of the stations having a code call designated by the symbol "-". In other words, the symbols employed in the Typical table of codes not only represent the energized or deenergized conditions of the respective code responsive relays, but also represent the positions of certain code jumpers at each station.

As the code jumpers 205, 206 and 207 are arranged in accordance with the code combinations or code calls, and as a particular combination occurs but once, then it is obvious that with the code responsive relays assuming corresponding positions at all stations, the chain circuit for transferring the step-by-step operation from the code channel stepping relay bank to the message channel stepping relay bank will be completed at but one station.

Should a greater number of stations be employed with the system, a greater number of code responsive relays would be required, three such code responsive relays providing eight combina- 75

tions, four relays sixteen combinations, five relays thirty-two combinations and so on in geometrical progression with the constant ratio of two.

With reference to the control office (see Figs.

- 5 1A and 1B), the code responsive relays *a*, *b* and *c* are in energized, deenergized and energized positions respectively, the relays *a* and *c* having been energized through the same circuits as traced for relays A and C. These code responsive relays *a*, *b* and *c* each have stick circuits closed when they are energized until the end of the operating cycle in which they are energized. For example, the stick circuit of the relay *a* is closed from (+), through front contact 58 of relay SL⁰, wires 214, 215 and 216, upper winding of relay *a*, front contact 217 of relay *a*, to (-).

A chain circuit is completed by the code responsive relays for transferring the stepping operation from the code channel stepping relay bank to a message channel stepping relay bank corresponding to the station which is selected in response to the code call as registered upon these code responsive relays.

The eight combinations or eight chain circuit selections which may be made by the code responsive relays *a*, *b* and *c* are brought out to eight suitable terminals to which the pick-up or lower winding of the first stepping relay in the message channel stepping relay bank of the corresponding station may be connected. For example, the message channel stepping relay bank for station No. 1 must be connected to the particular one of the eight terminals that will have the chain circuit completed when the code call assigned to the first station has been transmitted or received. Thus, the lower winding of the stepping relay 5⁰ is connected to the third terminal by a jumper connection indicated by a dotted line, thereby completing a pick-up circuit for this relay upon the energization of the line relay L⁰ in response to the fifth impulse applied to the stepping circuit. This pick-up circuit for the stepping relay 5⁰ is closed from (+), through polar contact 220 of relay L⁰ in a right hand position, wire 221, front contact 222 of relay SL⁰, wire 223, back contacts 224, 225 and 226 of stepping relays 1⁰, 2⁰ and 3⁰ respectively, front contact 227 of stepping relay 4⁰, wires 228 and 229, front contact 230 of code responsive relay *a*, back contact 231 of code responsive relay *b*, front contact 232 of code responsive relay *c*, through jumper 233, wire 234, lower winding of stepping relay 5⁰, wires 235 and 236, back contact 237 of stepping relay 6⁰, to (-). Thus, stepping relay 5⁰ is energized in multiple with the last code channel stepping relay LC⁰ and the relays 6⁰, 7⁰, 8⁰ and LM⁰ sequentially step in response to the application of their respective impulses to the stepping circuit.

In a similar manner, if the code responsive relays *a*, *b* and *c* were energized or deenergized in any other code combination, the corresponding message channel stepping relay bank would thereby be selected, that is, the step-by-step operation would be transferred to that stepping relay bank.

In the control office, the last code channel stepping relay LC⁰ is energized simultaneously with the first stepping relay of the message channel stepping relay bank which has been selected for the particular cycle of operation. The energization of the stepping relay LC⁰, opens the stick circuit of the stepping relay 4⁰ at back contact 238, thereby allowing the contacts of the relay 4⁰ to assume deenergized positions completing the message line to the message channel stepping

relay bank for the station selected (in this case the message channel stepping relay bank for station No. 1). Similarly, at each of the way stations, the last code channel stepping relay LC is energized upon application of the fifth impulse to the stepping circuit, thereby opening the stick circuit of the stepping relay 4 at every station. This removes the code responsive relay C at the respective stations from their multiple connection to the message line and the common return line. These relays LC remain energized until the end of the operating cycle through a stick circuit including front contact 121 of relay SL thereby locking up the step-by-step operation of each of the stations except the particular station which received its characteristic code call. At this station the stepping relay 5 is energized in multiple with the relay LC at that station and the step-by-step operation is transferred to the message channel stepping relay bank of that station, as heretofore explained.

Transmission of new controls.—After a station is selected in response to the transmission of its code call, the step-by-step operation in response to the impulses applied to the stepping circuit occurs in the message channel stepping relay bank at that station and in the message channel relay bank in the control office corresponding to that station. In this particular case, the message channel stepping relay bank at the first way station (see Figs. 2 and 1A) will have the respective relays 5, 6, 7 and 8 sequentially step in synchronism with the relays 5⁰, 6⁰, 7⁰ and 8⁰. The eighth step is followed by an extra step for purposes hereinafter pointed out.

Each message channel stepping relay bank in the control office for the respective way station is capable of connecting upon the respective channel circuits certain contacts on the levers of the corresponding station to the message line, in a manner such that the function control relays at the way station will be operated through the respective channel circuits in accordance with the position of the corresponding levers of that station located in the control office.

In this case, the control levers SML and SGL, associated with the first way station, have contacts which control the energization and the polarity thereof of the message channel circuits completed by the message channel stepping relay bank for this station. For example, upon the fifth step of this cycle of operation under consideration when the relays 5⁰ and 5 are energized and the stepping circuit is deenergized to mark off the message or execution period for that particular step, a circuit is completed from the contact 12 of the lever SML through the switch machine function control relay SMR at the first way station applying the proper polarity in accordance with the position of the lever SML.

As the operator moved the lever SML to a reverse position to operate the track switch TS to a reverse position, negative potential is applied from the terminal of the battery BT indicated as (B-), through contact 12 in a dotted line position, wire 240, front contact 241 of relay 5⁰, wire 242, back contacts 179, 185, 188 and 142 of relays 4⁰, 3⁰, 2⁰ and 1⁰ respectively, wire 143, back contact 144 of relay IR¹, wire 145, back contact 146 of relay IR², wire 147, front contact 148 of relay SL⁰, through the message line to the first way station, wire 150, front contact 151 of relay SL, wire 152, back contacts 153, 169, 186 and 187 of relays 1, 2, 3 and 4 respectively, wire 243, front contact 244 of stepping relay 5, wire 245, winding of relay 75

SMR, wire 246, front contact 247 of stepping relay 5, wires 248 and 158, to the common return line and thence to the mid-point of the battery BT in the control office.

5 This application of negative potential to the relay SMR causes its polar contact to be actuated to a left hand dotted line position which results in the operation of the switch machine and the controlling of the track switch TS to a reverse position, so that traffic may be routed onto or off of the passing siding S in accordance with the clearing of the governing signals 1A or 2A respectively.

15 With the lever SGL in a central position, the second message channel circuit is not energized during the message or execution period of the sixth step, thereby allowing the polar contact of the direction control function relay DR to remain in a position as formerly actuated.

20 However, the third message channel circuit is energized with negative potential with the lever SGL in a central position during the message or execution period of the seventh step thereby energizing the relay SGR through a circuit which 25 may be traced by analogy to the circuit traced for the relay SMR. Thus, the polar contact of relay SGR is actuated to a left hand position, which determines that the signals 1—1A and 2—2A shall display stop indications.

30 The manner in which these function controlling relays SMR, SGR and DR control their respective traffic controlling devices is only indicated by dotted lines, it being understood that the control may be accomplished in any suitable 35 manner, such for example as shown in the patent to S. N. Wight, Patent No. 1,889,457, dated November 29, 1932. It is also to be understood, that any number of function control relays may be employed for operating various other traffic 40 controlling devices the same as, or different, than those illustrated, these relays being operated in accordance with control contacts in the control office over message channel circuits provided by extra stepping relays.

45 If some other station had been selected, such for example as the second way station shown in Fig. 3, a message channel stepping relay bank corresponding to that station in the control office would be sequentially operated in synchronism 50 with the message channel stepping relay bank at the second way station. The channel circuits set up thereby would be governed by similar control levers SML and SGL (not shown) associated with the second way station. In other 55 words, the group of levers corresponding to each station is associated with a corresponding group of message channel stepping relays being permanently connected to the front contacts of the respective relays closing the proper channel circuits provided thereby.

60 *Transmission of old indications.*—As this cycle of operation was initiated in response to the movement of a control lever in the control office, it can be easily seen that one or more of the 65 controls resulting therefrom will be new controls, but in all probability the indications, transmitted during such a cycle of operation, will be old indications, that is, indications transmitted in accordance with the position of traffic controlling devices at that way station prior to the transmission of the controls, and as formerly transmitted.

70 Upon the seventh step, or more generally speaking, upon the step preceding each particular step assigned for the transmission of an indi-

cation impulse, a resistance is included in the stick circuit of the corresponding stepping relay in the control office. A drop in potential occurs across this resistance during the execution period of that step which is employed to actuate the 5 polar contact of an indication storing relay IS to a normal position. If on the next step, during the completion of its message channel circuit, the indication contact at the way station which governs this relay, is closed, then the polar contact of this indication storing relay will be actuated to an opposite or reverse position. This 10 actuation will not be cancelled until the station is again selected, in order to insure that the indication will be stored and be a true indication of 15 the position of the governing indication contact at the way station. If the governing indication contact is not closed, then this polar contact will remain in its normal position as controlled by the potential drop across the resistance. 20

This has been more specifically pointed out for the indication storing relay IS which has a resistance R connected in series with the stick circuit of the stepping relay T. When current flows through this stick circuit including the 25 resistance R, a drop in potential is created across the resistance which causes current to flow from its left hand terminal through wire 250, lower winding of relay IS, wire 251, to the right hand terminal of this resistance. It is to be understood of course, that the source of supply furnishing current for the stick circuit, also furnishes this current for the relay IS. This flow of current actuates the polar contact of relay IS to a left-hand position (as shown). 30

35 During the message or execution period of the eighth step, a channel circuit is closed or left open in accordance with the position of the contacts of the track relay T. In this case, there is no train upon the detector track section TK, 40 therefore the track relay T will be energized. Thus, this indication channel circuit will remain open allowing the polar contact 252 of relay IS to remain in its left hand position, as actuated by the drop in potential across the resistance R. 45

If this circuit had been closed due to the de-energization of the track relay T, this polar contact 252 of the relay IS would be operated to a right hand position and indicate the occupied 50 condition of the detector track section TK by the energization of the indicator lamp I, through a circuit obvious from the drawings.

55 It is to be understood that a greater number of channel circuits can be employed to provide a greater number of indication message channel circuits, so that indication of various other conditions such as indication of the position of signals, position of switches, and the like, may be provided for assisting the operator in directing traffic over that part of the railroad under his 60 supervision.

65 It is to be understood that indication storing relays similar to the relay IS are to be associated with each way station and are similarly controlled over channel circuits provided by the message channel stepping relay bank corresponding to the station with which they are associated.

70 *End of operating cycle.*—After the eighth stepping relay in the message channel stepping relay bank in the control office corresponding to the station selected and the corresponding message channel stepping relay bank at the selected station has been energized, another impulse is placed upon the stepping circuit to cause the 75

last message channel stepping relay LM^0 to be energized. This opens the stick circuit of the stepping relay 8^0 . The relay LM^0 closes its own stick circuit and remains energized until the relay SL^0 is deenergized, but it also opens the stick circuits of the relays SR^1 , CD^1 , LS and CC at the contacts 37, 36 and 52. The deenergiation of the relay CC opens the stepping circuit at front contact 70 thereby causing the line relays L to remain deenergized. The starting relay S cannot be energized as long as the relay SL^0 is energized; and the stepping line cannot be energized until the relay CC is energized by the relay S . Hence, as the stepping line remains deenergized another cycle of operation cannot be initiated until the relay SL^0 has been deenergized, which occurs a predetermined time period after the last energization of the line relay L^0 . This insures that the relays SL at every station will be deenergized, at which time the system will be restored to a normal at rest condition, even if another cycle is to be initiated. However, if no control lever is moved or no new indication occurs at a way station, the system remains at rest.

Sequence of outgoing station selection.—It will be evident that the code responsive relays at each of the stations are capable of assuming but one combination of energized and deenergized positions, which combination is assumed in accordance with the particular channel circuits which are energized during the station selecting part of the operating cycle. Should two or more code calls or combinations of impulses be applied to the message line during the station selection part of the operating cycle, then the code calls would be mutilated and cause the selection of some station unintentionally.

This mutilation of code calls may be best understood with reference being made to the typical table of codes (see Fig. 5). If the code call No. 3, provided for the first way station, and the code call No. 6, provided for the second way station, are combined, it is obvious that the code call No. 6 is the one which is actually existent during the station selecting part of the operating cycle. Thus, the station having code call No. 6 assigned to it is unintentionally selected and erroneously controlled.

Of course the operator could be relied upon to actuate a lever for the selection of a particular station and then allow sufficient time for the controls to be transmitted in accordance therewith before operating another lever; but such a procedure would considerably handicap the operator in planning train movements and limit the extent of the territory which one operator could adequately supervise.

In accordance with the present invention, means is provided, whereby the control levers for the various stations may be moved simultaneously or in rapid succession, with said means automatically determining the sequence of the transmission of the proper code calls to prevent any mutilation thereof.

This means, which determines the sequence of out-going station selection by determining the code calls which are transmitted, includes a storing relay SR for each group of levers associated with a particular station, which storing relay is energized when any one of the levers of that particular group has been operated to a new position. The energization of a storing relay SR energizes its corresponding code determining relay CD when the system is at rest, or in a period of blank which occurs between two cycles of op-

eration. Each of these code determining relays CD provides that the code call of its corresponding station is transmitted with the character of the code call determined by its associated code jumpers, such for example as the code jumpers 160 and 162 associated with the first way station. However, the circuits controlled by the code determining relays CD and associated code jumpers are so interlocked that the impulses of only one code call may be transmitted over the message line during the station selecting part of a particular operating cycle.

If more than one of the code determining relays CD is energized at a time, the code jumpers corresponding to the particular energized code determining relay CD which is farthest to the left, are caused to govern the energization of the code channel circuits; while the code jumpers of the other code determining relays (which are energized) to the right of the above mentioned code determining relay do not effect the code channel circuits. At the end of the operating cycle this particular code determining relay, which determined the code call for that cycle, is dropped out and the next code determining relay to the right of it which is energized determines the call for the succeeding cycle of operation.

This may be best understood by assuming that both the relays CD^1 and CD^2 are energized (see Fig. 1A). The code jumpers 160 and 162 are then conditioned to control the code channel circuits as heretofore pointed out. However, the code jumper 261 associated with the relay CD^2 cannot effect the code channel circuit of the third step, due to the opening of back contact 184 of relay CD^1 , nor can either of the two other code channel circuits be effected by the code determining relays and code jumpers to the right of the relay CD^1 due to the open condition of back contacts 163 and 174.

It is obvious that when the relay CD^1 is deenergized the wires 164, 255 and 175 will then be connected to wires 256, 257 and 258 permitting the next code determining relay to the right (which is energized) to then control the code channel circuits. In other words, the code channel circuits pass through chain circuits including contacts on the code determining relays CD , in a manner that when a particular relay is energized, it is effective to prevent the control of every code determining relay to the right of it.

These code determining relays CD may be picked up when the relay SL^0 is deenergized as heretofore pointed out in connection with relay CD^1 . Thus, the particular code determining relay to the left, which is last energized during the time that the system is at rest or in a period of blank, is the one to transmit or determine the code call for the succeeding cycle of operation. The energization of the relay SL^0 prevents the mutilation of a code call during transmission.

If the operator moves several levers while the system is in operation, the corresponding storing relays SR are energized, but the code determining relays CD corresponding to those storing relays are not energized until the end of that cycle of operation, at which time they are energized upon deenergization of the relay SL^0 ; but these code determining relays CD transmit the code calls in a sequence or order from left to right.

It is of course to be understood, that these relays SR do not have to be associated in an order in accordance with the geographic location of the stations, but each one of these stor-

ing relays may be associated with any way station desired. For convenience the storing relay SR¹ has been associated with the group of levers for the first way station, the storing relay SR² has been associated with the group of levers for the second way station (not shown), and so on; but these storing relays SR¹, SR² could be associated with the other groups of control levers thereby changing the order of sequence in which the code calls of the respective stations are transmitted.

Incoming station selection.—The selection of stations for the transmission of out-going controls, the transmission of these controls and the repetition of the indications associated therewith, is all accomplished, as above explained, over the message circuit. Also, the same message circuit is employed for the transmission or communication of impulses to accomplish station selection for incoming indications, the transmission of those indications and the repetition of the controls associated therewith.

This utilization of the message circuit to transmit impulses in either direction is made possible, due to the manner in which the system is conditioned for either out-going station selection or incoming station selection.

As there are many trains passing over the system under the supervision of the operator, these trains may arrive at OS-ing points simultaneously, thereby providing indications at several stations which are ready for transmission at the same time. Likewise, the operator may transmit controls to several stations, the resulting operations being completed at substantially the same time, thereby providing indications at the several stations to be transmitted to the control office. However, as only one way station can be in communication with the control office for incoming station selection during a particular cycle of operation, means is provided whereby the station having new indications to transmit which is nearest the control office is made superior to the others and locks them out, so to speak, during the initiation of the system from the field. In other words, the initiation from the field is employed as the conditioning period for determining which way station is superior and determining that the cycle of operation shall be for incoming station selection. Thus, the conditioning channel circuit completed after the initiation of the system, as heretofore explained, will not be energized but will be left deenergized permitting the selection of the station in accordance with code call transmitted from the field.

For convenience, the selection of a single station and the transmission of its indications, controls and the like will be explained first, with the means of lock-out for station superiority during incoming station selection pointed out at a later time.

Automatic starting.—Whenever a change takes place in the occupancy of a detector track circuit, the position of a switch, signal or other traffic controlling device which is required to provide an indication in the control office, the system is automatically set into operation for the selection of the corresponding station. This change in conditions at a way station is registered by the momentary closure of the pick-up circuit of the change relay CH at that station. This momentary energization of the relay CH is sufficient to actuate its contacts to energized positions, which completes a stick circuit for maintaining the change relay energized until the

corresponding station has been selected and the new indication transmitted.

For convenience, let us refer to the first way station (see Fig. 2) and consider in detail the operation of the system when initiated from the field due to a change in detector track circuit occupancy, such an operation being considered as representative of all such operations which might occur due to a change in position of a signal, track switch or the like at this station or any other station.

The passage of a train onto or off the detector track section causes the contacts of relay T to assume deenergized or energized positions respectively, for reasons well understood. This movement of the contacts of the relay T causes the momentary or make-before-break contact of the relay to complete a circuit from (+), through momentary contact 265 of relay T, wires 266 and 267, winding of relay CH, to (-). This energizes the relay CH causing a stick circuit to be closed from (+), through back contact 268 of stepping relay 5, wire 269, front contact 270 of relay CH, wires 271 and 267, winding of relay CH to (-).

With the system at rest, the energization of the relay CH shorts the message line to the common return line thereby completing a circuit from (B+), through back contact 272 of cycle controlling relay CC, wire 273, winding of field starting relay FS, wire 274, back contact 275 of relay SR², wire 276, back contact 277 of relay SR¹, wire 278, back contact 148 of relay SL⁰, through the message line wire to the first way station, wire 150, back contact 151 of relay SL, wire 279, front contact 280 of relay CH, wire 281, upper winding of relay FC, wires 282, 283, 157 and 158, to the common return wire and thence to the midpoint of battery BT. The closure of this starting circuit energizes the field starting relay FS in the control office and the field control relay FC at this way station. The field control relay FC is maintained energized, until that station has been selectively operated, by a stick circuit closed from (+), through back contact 297 of relay 8, wire 298, front contact 299 of relay FC, lower winding of relay FC, to (-). In a similar manner, the field starting relay FS and the relay FC at any other way station can be energized in series should the change relay at some other station become energized with the system at rest.

The energization of the field starting relay FS closes a pick-up circuit for the local starting relay LS from (+), through front contact 284 of relay FS, wires 285 and 47, upper winding of relay LS, to (-). The relay LS becomes energized and closes its stick circuit, and also energizes the starting relay S, which in turn energizes the cycle controlling relay CC, all in a manner as heretofore pointed out for "manual starting". Thus, the system is initiated into operation as the result of the change in the condition of occupancy of the detector track section TK at the first way station. The energization of the change relay CH at that station for any other change in condition of traffic controlling devices, or the change relay at any other station, would result in a similar automatic initiation of the system.

Energization of the field starting relay FS also accomplishes the energization of a field control relay fc in the control office from (+), front contact 286 of relay FS, wires 287 and 288, winding of relay fc, to (-). This relay closes its stick circuit from (+), through back contact 289 of relay

LC⁰, wire 290, front contact 291 of relay fc, wire 288, winding of relay fc, to (-). The energization of the cycle controlling relay CC deenergizes the field starting relay FS at back contact 272, but this occurs subsequent to the energization of the relay fc as the energization of relays FS and S intervene between the energization of the relays FS and CC.

The energization of this field control relay fc determines that the conditioning channel circuit completed during the execution period of the first step shall be deenergized. In other words, the energization of the field starting relay FS determines that the cycle of operation is one for in-coming station selection which conditioning of the system is accomplished during the initiation thereof from the field.

Transmission and registration of code calls from a way station.—Assuming the system to be automatically initiated into operation as above explained and impulses to be placed upon the stepping circuit causing the sequential and simultaneous operation of the step-by-step means at the control office and at each way station, we will now consider the selection and registration of the first way station which is now ready to send in new indications.

During the execution period of the first step, the channel circuit for that step is deenergized. Thus, the relay CR at each of the way stations is left deenergized. This means that the code responsive relays at each of the way stations, except the way station where the relay FC is energized, are not connected to the message line and common return line on their respective channel circuits as explained for out-going station selection, as the front contact 172 of the relay CR is open.

However, the relay FC at the first way station, where the change has occurred resulting in the initiation of the system from the station, is energized. The energization of this field control relay FC closes its front contact 171 which connects those code responsive relays, which are necessarily energized for the selection of that station, through their respective channel circuits to the message line and the common return line. In the control office the energization of the field control relay fc causes positive potential to be applied to the message line from the battery BT on each of the code channel circuits. Thus, during the execution period of those steps where the channel circuits have the code responsive relays connected to the message line and the common return line, a circuit is completed which energizes the corresponding code responsive relays in the control office and at the station which is transmitting the code call.

More specifically, during the execution period of the second step, a circuit is completed from the positive terminal of battery BT indicated as (B+), through front contact 165 of field control relay fc, wire 166, lower winding of code responsive relay a, wire 167, front contact 168 of stepping relay 2⁰, back contact 142 of stepping relay 1⁰, wire 143, back contact 144 of relay IR¹ wire 145, back contact 146 of relay IR², wire 147, front contact 148 of relay SL⁰, through the message line to the first way station, wire 150, front contact 151 of relay SL, wire 152, back contact 153 of counting relay 1, front contact 169 of stepping relay 2, wire 170, lower winding of code responsive relay A, code jumper 180, through code bus 200, front contact 171 of relay FC, wires 283, 151 and 158, to the common return line and thence to

the mid-point of battery BT. Thus, the code responsive relays a and A, at the control office and at the first way station respectively, are energized and maintained energized through their stick circuits.

During the execution period of the third step, positive potential is applied to that channel circuit through front contact 292 of relay fc and the code responsive relay b, but the code jumper 181 at the first station connects the code responsive relay B to the code bus 201 which inasmuch as front contact 172 of relay CR is open, this channel circuit is not completed during the execution period of this third step.

However, during the execution period of the fourth step, inasmuch as the code jumper 182 is connected to the code bus 200 at the first way station, the channel circuit for that step is completed to permit current to flow from the positive terminal of the battery BT indicated as (B+), through front contact 176 of relay fc, wire 171, lower winding of code responsive relay c, wire 178, front contact 179 of stepping relay 4⁰, back contacts 185, 168 and 142 of stepping relays 3⁰, 2⁰ and 1⁰ respectively, wire 143, back contact 144 of relay IR¹, wire 145, back contact 146 of relay IR², wire 147, front contact 148 of relay SL⁰, through the message line to the first way station, wire 150, front contact 151 of relay SL, wire 152, back contacts 153, 169 and 186 of stepping relays 1, 2 and 3 respectively, front contact 187 of stepping relay 4, wire 188, lower winding of code responsive relay C, code jumper 182, code bus 200, front contact 171 of relay FC, wires 283, 151 and 158, to the common return line and thence to the mid-point of battery BT.

Thus, the group of code responsive relays in the control office are energized and de-energized in correspondence with the group of code responsive relays at the first way station, both groups assuming positions in accordance with the code call of the first way station. This correspondence causes the step-by-step operation at the control office and at the first way station to be transferred from the respective code channel stepping relay banks to the message channel stepping relay banks corresponding to the first way station.

From the above description it can be seen, that each of the channel circuits, having code responsive relays connected therein, receive energy in the control office due to the energization of the field control relay fc, while the actual completion of each channel circuit is dependent upon the position of the respective code jumper at the way station connecting that channel to either the code bus 200 or 281. If the code jumper connects the channel circuit to the code bus 200, that channel circuit is closed and current flows therein to pick up the corresponding code responsive relays at the control office and at the way station; while if the code jumper connects that channel circuit to the code bus 281, that channel circuit is not closed and current does not flow therein.

For example, the first way station has the code call No. 3 (see Fig. 5) assigned to it which requires the respective channel circuits of the code responsive relays A, B and C to be energized, de-energized and energized. In accordance with this code call, the code jumpers 180 and 182 are connected to the code bus 200, thereby causing the respective channel circuits to be closed and energized upon their respective steps, while the connection of the code jumper 181 to the code

bus 201 causes its respective channel circuit to be deenergized. In other words, the code jumpers 180, 181 and 182 at each station must be arranged in accordance with the code call of that station, each code jumper being connected to the code bus 200 if its channel circuit is to be energized as represented by a symbol "+" in the Typical Table of Codes, while if such channel circuit is to be deenergized as represented by a "-" symbol then that code jumper is connected to the code bus 201.

Transmission of old controls.—Upon the application of the next impulse (fifth) to the stepping circuit for this cycle of operation, the last code channel stepping relay LC at the control office and at each of the way stations is energized. At the control office the code responsive relays *a*, *b* and *c* are assuming positions in correspondence with the code call of the first way station, hence upon the application of this fifth impulse, the stepping relay 5° will be energized in multiple with the relay LC°.

At the first way station the code responsive relays *A*, *B* and *C* are assuming positions in correspondence with the code call of that station, therefore upon the application of the fifth impulse the stepping relay 5 will be energized in multiple with the last code channel stepping relay LC, in a manner as heretofore pointed out. At all other way stations as the code responsive relays at those stations are all deenergized the step-by-step operation will be discontinued with the energization of the relays LC at those stations.

Upon the energization of the relay LC° in the control office, the field control relay *fc* is deenergized due to the opening of its stick circuit at back contact 289 of relay LC°.

At the first way station the change relay CH is deenergized upon the energization of the stepping relay 5 due to the opening of back contact 288. As this stepping relay 5 is deenergized upon the next step, the change relay is then conditioned for storing such other changes in position of traffic controlling devices at that station as may occur subsequent to this fifth step.

The step-by-step operation of the system continues in a manner heretofore explained, closing the control channel circuits for the relays SMR, DR and SGR, causing them to be controlled in accordance with the positions of their corresponding levers in the control office. It is not considered necessary to describe and specifically point out the channel circuits for the function control relays SMR, DR and SGR, nor to assume certain positions for the control levers, as such operations have been previously explained. However, it is to be noted in this connection, that in practice the lever SGL would be in such a position as to have previously caused the clearing of one of the signals 1—1A and 2—2A in order for a train to pass onto the detector track section TK. However, it is to be assumed that such a condition or some other similar condition exists and that the controls in accordance therewith have been previously transmitted. Thus, the closure of the channel circuits for the control of the function control relays SMR, DR and SGR is a repetition and serves to check and maintain these function control relays in their previously operated positions.

Transmission of new indications.—Assuming the system to operate up to the eighth step as previously explained, the indication storing relay IS is energized on the seventh step by the drop 75 in potential across the resistance R which insures

that the contact 252 is actuated to a left hand position.

If the track relay T is deenergized, the channel circuit closed during the execution period of the eighth step will be energized; but if the track relay is energized, that channel circuit will remain deenergized. If the channel circuit is energized, the polar contact 252 of the indication storing relay IS will be operated to a right hand position energizing the indicator lamp I in the control office, indicating the occupied condition of the detector track section TK in accordance with the shunted or deenergized condition of the track relay T. This energized condition of the indicator lamp I will exist, although the station is again selected causing the indication storing relay IS to be energized by the drop in potential across the resistance R, if the track relay is still deenergized, as the indication storing relay IS would again be energized through its respective channel circuit on the eighth step to again actuate the polar contact 252 to a right hand position.

For convenience assuming that the track relay is deenergized as heretofore pointed out to accomplish the energization of the relay CH, this indication channel circuit closed during the execution period of the eighth step from the positive terminal of the battery BT indicated as (+), through upper winding of indication storing relay IS, wire 300, front contact 301 of stepping relay 8°, back contacts 302, 303 and 241 of stepping relays 7°, 6°, and 5° respectively, wire 242, back contacts 179, 185, 168 and 142 of stepping relays 4°, 3°, 2° and 1° respectively, wire 143, back contact 144 of relay IR¹, wire 145, back contact 146 of relay IR², wire 147, front contact 148 of relay SL°, through the message line to the first way station, through wire 150, front contact 151 of relay SL, wire 152, back contacts 153, 169, 186 and 187 of stepping relays 1, 2, 3 and 4, wire 243, back contacts 244, 304 and 305 of stepping relays 5, 6 and 7 respectively, front contact 306 of stepping relay 8, wire 307, back contact 308 of track relay T, wire 309, front contact 310 of stepping relay 3, back contacts 311, 312 and 247 of stepping relays 1, 6 and 5 respectively, wires 248 and 158 to the common return line, and thence to the mid-point of battery BT.

Also, upon the energization of the eighth stepping relay, the stick circuit for the field control relay FC at the first way station is opened at back contact 297 of stepping relay 8.

End of operating cycle.—Upon the application of the next impulse (ninth) to the stepping circuit, the last message channel stepping relay LM° included in the message channel stepping relay bank for station No. 1, is energized. The energization of this stepping relay causes the deenergization of the local starting relay LS and the cycle controlling relay CC, thus causing the system to be returned to the at rest or period of blank condition in a similar manner, as explained for the end of an out-going station selection cycle of operation.

When the train passes off the track section TK, the change relay CH will be again energized causing the system to operate through another cycle of out-going station selection. Such a cycle of operation will be similar to the one just explained with the exception that the indication channel circuit of the eighth step will not be energized. This will leave the polar contact 252 of relay IS in a left hand position to which it is actuated on the preceding step (seventh). Other operations will be understood by analogy.

Non-selecting code call.—As heretofore pointed out, assuming three station selecting or code steps, with a choice of energization or deenergization of the message line on each step, a selection of eight different way stations has been assumed. As a matter of fact, in order to avoid certain complications and irregularities in operation, the code call represented as code call No. 8 in the Typical table of codes is preferably not used or assigned to any station.

As above explained, during a cycle of in-coming station selection the code responsive relays at the way stations are all deenergized except at the station which is transmitting or registering its code call in the control office. Thus, should some station having a code call, for example, as code call No. 5 shown in a Typical table of codes, be transmitting its code call to the control office, then the code responsive relays at all other stations would be deenergized due to the deenergization of the CR relay at each of the stations. If one of these stations which is not transmitting should have the code call No. 8 assigned to it, it is obvious that the step-by-step operation would be transferred from the code channel stepping relay bank to the message channel relay bank at that station although its code responsive relays had not been actively controlled, which they could not, in this case, as some other station is sending in. Should this station having code call No. 8 assigned to it be nearer the control office than the station transmitting its code call, this station would then be falsely controlled.

However, if in extreme cases it is necessary to use the code call having each code channel circuit deenergized (such as code call No. 8), then such code call would necessarily have to be assigned to the last way station in the system so that its erroneous selection would cause no false controls due to the opening of the message line at such station as would then be transmitting to the control office, which condition is to be hereinafter pointed out.

Such a code call having each code channel circuit deenergized is preferably not used, as the breaking of a wire, a poor contact or the like might falsely select such a station. In other words, a station which is selected without being actively controlled may be selected for various undesirable causes not under the control of the operator. Thus, such a code call is preferably not employed with the system of the present invention.

Lock-out superiority between the control office and way stations.—It is desirable in a system of this type that the operator shall be able to control any station at any such time he may desire to do so. In accordance with the present invention, this feature of control office superiority is provided by carrying the field starting circuit through back contacts on each of the storing relays SR associated with each of the stations, which is specifically shown as back contact 271 for relay SR¹ and back contact 275 for relay SR².

If the operator moves a control lever and energizes a storing relay SR slightly prior to the energization of a change relay CH in the field, the resulting cycle of operation is one for out-going station selection with the next succeeding cycle of operation being one for in-coming station selection. This is because the field starting circuit is opened by a back contact of an SR relay.

If the operator moves a lever during a cycle of operation for in-coming station selection, the

field starting circuit is opened during the period of blank succeeding that cycle of operation, thereby causing the subsequent cycle to be one of out-going station selection as the field control relay fc is not energized.

If the operator moves a control lever and energizes a storing relay SR slightly subsequent to the energization of the field starting relay FS, the resulting cycle of operation is for in-coming station selection as the field control relay fc is energized regardless, as soon as the field starting relay FS has been energized.

Lock-out superiority between way stations for incoming station selection.—It has been previously stated that two or more stations may have new indications to communicate to the control office at the same time, such as for example, indications due to a change in the occupied condition of the track circuits or various other changes in traffic controlling devices which happen to occur simultaneously.

In a communication system of this type, it is necessary that only one code call shall be transmitted over the message line for a particular cycle of operation as the combining of two or more code calls will cause a mutilation of those code calls and form some other code call which results in the selection of an undesired station. This has been pointed out in the case of out-going station selection where the code is determined in the control office.

In this case, the code is determined at the way stations and means is provided preventing more than one way station determining the code during any particular cycle of operation. This feature of the present invention is accomplished by the field control relay at each of the way stations. The energization of a field control relay, such as field control relay FC at the first way station, opens the message line at back contact 315 of that relay, thereby opening the message line to subsequent way stations. This prevents any subsequent way station from transmitting its code call over the message line to the control office. The particular way station which transmits its code call and which is registered in the control office is the one nearest the control office which has its field control relay FC energized.

It is obvious from the drawings that a field control relay FC cannot be energized during the operation of the system as its pick-up or energizing circuit is opened at back contact 151 of the slow acting relay SL at each way station. This prevents the interference between stations during the operation of the system.

Repeat operations.—Each storing relay SR preferably has associated therewith a self restoring push button PB, which may be employed by the operator to energize the corresponding storing relay. Such energization of a storing relay results in the selection of the corresponding station without the operation of a traffic controlling device at that station, such as would occur with the operation of a control lever. If the push button is momentarily actuated by the operator, the system will operate through one cycle transmitting both the controls and indications associated with the particular station selected and then return to its normal at rest condition; but if the operator maintains the push button in an actuated position, the system will continue to operate through successive cycles continuously transmitting both the controls and indications associated with the particular station selected.

In other words, the operator is provided with

means for checking the indications at the various way stations as well as the controls associated therewith, which means may also be employed to continuously select a station in the event that the operator is waiting for an indication from that particular station. This feature of continuous selection enables the operator to receive an indication from a particular station during the next cycle of operation after the change or indication occurs at that station, regardless of the various changes and indications present at other stations nearer the control office which would ordinarily be transmitted, if the operator was not continuously selecting that particular station.

These features have been more specifically illustrated for the first way station by the showing of push button PB¹ which, when actuated, energizes the storing relay SR from (+), through push button PB¹ in an actuated position, wires 316, 18 and 19, winding of relay SR¹, to (-). The energization of the storing relay SR¹ results in the initiation of the system and selection of the station associated therewith in a manner as heretofore explained and pointed out.

Summary.—From the foregoing explanation of the various devices, individual steps in the operation of the system, characteristic features, and the mode of operation, the various advantages of the system as a whole can be readily appreciated; and it is believed that a brief general statement will suffice to make clear the nature of the invention, both broadly and specifically.

A stepping line and a common return line form a stepping circuit extending from the control office through all of the stations; while a message line and the common return line are employed to form message or channel circuits including at certain times the control office and all of the way stations and including at certain other times the control office and a particular way station in response to impulses applied to the stepping circuit, which stepping impulses are of alternate polarities.

The system is set into operation when the operator actuates a control lever or a starting button in the control office, or when a change relay CH is energized at any field station as the result of a change in the position or condition of the traffic controlling devices at that station having indications which are to be indicated in the control office.

Each cycle of operation is made up of an initiation period, a conditioning step, a number of station selecting or code steps, a number of control steps, and a number of indication steps.

The initiation period for out-going station selection is for starting the system into operation only; while for incoming station selection it is employed for conditioning a station for transmitting its code call.

The conditioning step which is the first step taken after initiation is employed for conditioning the system for out-going station selection.

The co-action of these two conditioning functions of the system may be briefly summarized by considering what is actually accomplished. The conditioning of a station for incoming station selection is accomplished by the energization of its field control relay FC which connects those code responsive relays at that station to the message line which must be energized to accomplish the selection of that station. Thus, with energy applied to the message line at the control office on each of the code steps, the way station may determine which code steps shall be energized.

The system is conditioned for out-going station selection by energizing the first conditioning step which energizes a code response control relay CR at each station. This connects all of the code responsive relays at every station to the message line. Thus, by energizing certain of the code channel circuits in the control office, the code call may be determined therein and a station selected thereby. These conditioning features are necessary in a system of this type employing multiple message circuits.

The code responsive relays at the control office transfer the step-by-step operation from the step-by-step means closing the code channel circuits to the step-by-step means closing the message channel circuits for the station having its code call registered by the code responsive relays. Similarly, the step-by-step operation is transferred from the code channel closing step-by-step means at the way station where the code responsive relays are in positions corresponding to the code call of that station.

The sequential and synchronous operation of the step-by-step means in the control office corresponding to the selected station and the step-by-step means at the selected station, closes channel circuits for the transmission of control impulses and indication impulses regardless of whether the station is selected from the control office or whether the station has determined its own selection.

The system continues to operate through successive cycles of operation with an intervening period of deenergization of the stepping circuit so long as there are new controls stored up in the control office or new indications stored up in the field stations. The order or sequence in which controls are transmitted to the stations, when such controls for plurality of stations are ready at the same time, is determined by the manner in which the storing relays are connected to the respective groups of levers associated with the various stations. The order or sequence in which a plurality of stations (all ready at the same time) transmit new indications, is determined by the relative geographic location of those stations. In this connection, the code calls which are employed to limit the number of steps required to select a station may be assigned to any station regardless of its geographic location or relative importance.

Relays are employed for all operations. The equipment for each of the field stations is the same except for certain jumper connections as heretofore pointed out, which connections may be changed to alter the code call of that equipment to some other code call. Thus, any particular equipment may be easily and quickly replaced in case of trouble by a spare equipment.

Various other characteristic features and advantages of the invention will be apparent. The specific organization of the centralized traffic control system shown and described is merely one illustrative specific embodiment of the present invention; and it is to be understood that various modifications, adaptations and additions may be made to this specific embodiment without departing from the spirit or scope of the invention, with the appended claims pointing out the novel features and limitations of the present invention, rather than the foregoing description thereof.

What I claim is—

1. In a centralized traffic controlling system for railroads, a control office, a plurality of field

- stations, a series stepping circuit extending through the several stations, means at the control office for impulsing said stepping circuit at time spaced intervals, step-by-step means in the 5 control office and at each station all operated synchronously by the impulses on said stepping circuit, a message line connecting said control office and each of said stations, a plurality of channel circuits closed by said step-by-step 10 means at said control office and at each of said stations each of which includes said message line, and means at said control office and at each station responsive to impulses placed on each of said channel circuits.
- 15 2. In a centralized traffic controlling system for railroads, a control office, a plurality of field stations, step-by-step means at said control office and at each of said stations all operated synchronously, a plurality of channel circuits closed 20 by said step-by-step means, each of said channel circuits including said control office and each of said stations in multiple, means placing any one of a plurality of combinations of impulses on said channel circuits, said combinations each 25 corresponding to a code call characteristic of a particular station, and means at each field station responsive to said impulses, said means being effectively actuated to select a station only when said combination of impulses form a code call 30 characteristic of that station.
3. In a centralized traffic controlling system for railroads, a control office, a plurality of field stations, step-by-step means at said control office and at each of said stations all operated synchronously, conditioning means at each of said 35 stations, means at said control office for actuating said conditioning means at each of said stations, a plurality of channel circuits closed by said step-by-step means, each of said channel 40 circuits including said control office and each of said stations in multiple only when said conditioning means is actuated from said control office, means placing any one of a plurality of combinations of impulses on said channel circuits, said 45 combinations each corresponding to a code call characteristic of a particular station, and means at each station responsive to said impulses, said means at a particular station being effectively actuated to select that station only when said 50 combination of impulses form a code call characteristic thereto.
4. In a centralized traffic controlling system for railroads, a control office, a plurality of field stations, step-by-step means at said control office and at each of said stations all operated synchronously, a field control means at the control office and at each of said stations, one or more traffic controlling devices at each of said stations, means at each station for actuating said 55 field control means at that station and at said control office when any one or all of said traffic controlling devices at that station are operated, a plurality of channel circuits closed by said step-by-step means, each of said channel circuits is 60 including in series only said control office and said station at which said field control means is actuated, means at said station placing a combination of impulses on said channel circuits corresponding to the code call characteristic of that 65 station, and means in said control office registering said combination of impulses.
- 70 5. In a centralized traffic controlling system for railroads, a control office, a plurality of field stations, step-by-step means at said control office and at each of said stations all operated synchronously,

5 chronously, a plurality of code responsive relays at each station sequentially governed on consecutive steps by said step-by-step means, a message circuit connecting the control office and the several stations, and means including said message circuit for energizing or leaving deenergized the corresponding code responsive relays at each station on corresponding steps of said step-by-step means.

6. In a communication system of the synchronous selector type, a control office, a plurality of field stations, step-by-step means in the control office and at each station all operated synchronously, a message circuit extending from the control office to the several stations, 10 conditioning means at the control office and at each station for controlling the energization of the message circuit on a plurality of steps taken by said step-by-step means, manually operable means for causing said conditioning means in 15 the control office to control said message circuit in accordance with a code call of a particular station, automatic means at each station causing said conditioning means at that station to control said message circuit in accordance with 20 the code call characteristic of that station, and means preventing automatic control of said conditioning means at the several stations when said manually operable means is actuated.

7. In a communication system of the synchronous selector type, a control office, a plurality of field stations, a message line and a common return line both extending from the control office through the several stations, step-by-step means at the control office and at each station all operated synchronously, a group of code responsive relays at the control office sequentially placed in message circuits, including said message line and said common return line, by said step-by-step means, field control means at each station, 30 a group of code responsive relays at each station, certain relays of said group being connected in series with corresponding relays of said control office group respectively on corresponding steps by said step-by-step means through said 35 message circuits including said message line and said common return line when said field control means at that station is actuated, and means opening said message line extending to subsequent stations.

8. In a centralized traffic control system for railroads, a control office, a plurality of field stations, a stepping circuit extending from the control office through the several stations, a message circuit extending from the control office 55 to the several stations, step-by-step means at the control office and at each station operated synchronously over said stepping circuit, station selecting means at each station responsive to impulses on said message circuit on each step, 60 station registering means at the control office responsive to impulses on said message circuit on each step, traffic controlling devices at each station, manually operable control levers in the control office, indication storing means in the 65 control office, indication contacts at the stations, whereby operation of the system to select a station automatically causes said traffic control devices to be actuated in accordance with said control levers and said indication storing means to 70 be actuated in accordance with said indication contacts over said message circuit and subsequent to actuation of said station selecting means of a particular station and subsequent to registration of that station.

9. In a centralized traffic control system for railroads, a control office, a plurality of way stations, a stepping circuit, automatic impulsing means for placing a series of impulses on said stepping circuit, step-by-step means at each of said stations and at said control office all operated in synchronism by each impulse of said series of impulses applied to said stepping circuit, and a starting circuit extending between said control office and said field station capable of being closed at each station only a predetermined time after said automatic impulsing means has stopped operation. 5
10. In a centralized traffic control system for railroads, a control office, a plurality of way stations, a stepping circuit extending from the control office through the several way stations, impulsing means for placing impulses on said stepping circuit, step-by-step means at the control office and at each way station all operated in synchronism, a message line extending from the control office through the several stations, a starting circuit including said message line capable of being closed at each way station when said stepping circuit is not being impaled, message circuits including said message line closed by said step-by-step means in operation, and means disconnecting at a station said message line extending to subsequent stations when said starting circuit has been closed at that particular station. 15
11. In a centralized traffic control system for railroads, a plurality of field stations, a message line and a common return line extending from said control office through said field stations, step-by-step means at the control office and at each of said field stations operated in synchronism, a plurality of channel circuits closed by said step-by-step means each of said channel circuits including said message line and said common return line, means placing any one of a plurality of combinations of impulses on said channel circuits each of said combinations corresponding to a code call characteristic of a particular station, and means at the control office and at each of said field stations responsive to said combinations of impulses, said means being actuated to select a particular station only when said combination of impulses forms a code call characteristic of that station. 25
12. In a centralized traffic control system for railroads, a control office, a plurality of field stations, step-by-step means at the control office and at each of said field stations all operated in synchronism, a message line circuit connecting said control office and said field stations, a plurality of code relays at said control office and at each of said field stations, and means including said step-by-step means for connecting said code relays successively in multiple across said message circuit at each of said field stations and in series with said message circuit at said control office, whereby the corresponding code relays at the several stations may be simultaneously controlled over said message circuit. 35
13. In a centralized traffic control system for railroads, a control office, a plurality of field stations, step-by-step means at the control office and at each of said field stations operated synchronously for closing a plurality of channel circuits during each operating cycle, a code conditioning relay at each field station controlled on the first channel circuit of each operating cycle, a plurality of code responsive relays at each field station controlled on the remaining channel circuits of each cycle in accordance with the con- 40
5. trol of said code conditioning relay, and means in the control office placing any one of a plurality of combinations of impulses on said remaining channel circuits of a particular cycle, each of said combinations corresponding to a code call characteristic of a particular station, and means including said code responsive relays for selecting said station for a particular cycle in accordance with the particular combination of impulses placed on said remaining channel circuits of that particular cycle. 5
10. 14. In a centralized traffic control system for railroads, a control office, a plurality of field stations, step-by-step means at the control office and at each of said stations operated synchronously, a station control relay at the control office and at each of said field stations, one or more traffic controlling devices at each of said field stations, means at each field station for actuating said station control relay at the control office and at a particular station when any one or all of said traffic controlling devices at that station are operated, and a plurality of channel circuits closed by said step-by-step means each of said channel circuits including in series a code responsive relay at the control office and a code responsive relay at that station where said station control relay is actuated for placing a combination of impulses on said channel circuits corresponding to the code call characteristic of that station, whereby said station is registered in the control office for the subsequent transmission of indications from said field station. 15
20. 15. In a centralized traffic control system for railroads, a control office, a plurality of field stations, a message line and a common return line connecting said control office with said field stations, a source of energy in said control office, code determining means in said control office and at each field station, code responsive means at 30 said control office and at each field station, step-by-step means at the control office and at each field station normally at rest and capable of operating synchronously to establish a plurality of channel circuits, initiating means at the control office and at each field station for initiating said step-by-step means, means including said source, said code determining means and said code responsive means in the control office in series with said message line and said common return line 35
25. and in multiple with said code responsive means at the field stations upon the respective channel circuits completed by said step-by-step means when said step-by-step means are initiated by said initiating means in the control office, and means including said source and said code responsive means in the control office in series with said message line and said common return line, and the code responsive means and the code determining means at a particular field station 40 upon the respective channel circuits completed by said step-by-step means when said step-by-step means are initiated by the initiating means at that field station. 45
30. 16. In a centralized traffic controlling system for railroads, a control office; a plurality of field stations; a control line circuit extending from said control office through said field stations; impulsing means for impressing a series of impulses on said control line circuit; manually operable 50 means for initiating said impulsing means; a message circuit extending from said control office through said field stations, said circuit being normally open when said impulsing means is at rest; indication means at each field station for auto- 55

- 5 matically closing said message circuit when said
10 impulsing means is at rest; a starting relay and
a battery in the control office included in said
message circuit when said impulsing means is at
rest and said message circuit is closed by said
15 indication means; means preventing the closure
of said message circuit by said indication means
during the application of a series of impulses
on said control line circuit; and means preventing
20 the closure of said message circuit by said
indication means whenever said manually operable
means is actuated.
17. In a remote control system of the code type,
a code receiving apparatus comprising a contact
15 selectively controlled in accordance with the
character of the first element of the code for
determining whether the succeeding elements of
the code shall be received, a series of group select-
20 ing contacts controlled by the succeeding elements
of the code when that code is allowed to be
received, a plurality of different series of stepping
relays, and means selectively governed by said
group selecting contacts for selecting one of
25 said different series of stepping relays.
25. 18. In a remote control system of the code type,
a code receiving apparatus comprising a contact
selectively controlled in accordance with the
character of the first element of the code for
determining whether the succeeding elements of
30 the code shall be received, a series of group select-
ing contacts controlled by the succeeding elements
of the code when that code is allowed to be
received, a plurality of different series of stepping
relays, and means capable of sequentially
35 operating a particular series of stepping relays
when that series is selected by said series of group
selecting contacts.
19. In a centralized traffic controlling system
for railroads, a control office, a plurality of field
40 stations, two line wires connecting said control
office with said field stations, step-by-step means
at the control office and at each field station
synchronously operable through cycles of operation
45 for setting up a plurality of multiple channel
circuits over said line wires between said control
office and each of said field stations, code trans-
mitting means at the control office and at each field
50 station for impressing different code combina-
tions on said two line wires, each element of a code
being transmitted on its corresponding channel circuit,
means for selectively determining the character of the first code element
55 of each cycle for selecting whether the control
office or a field station code transmitting
means is to be effective to determine the remaining
code elements for that cycle, and means determin-
ing which particular field station code transmitting
60 means is to be rendered active if the character of the first element of the code is proper for a field station to transmit.
20. In a control system of the code type, a
stepping line circuit receiving series of time
spaced impulses, step-by-step means operated
65 through a cycle of operation by each series of
impulses on said line circuit for sequentially clos-
ing a series of contacts, a message line circuit re-
ceiving different series of code combinations, each
70 series having one element for each impulse on
said stepping line circuit, a series of code receiv-
ing relays one for each contact of said series,
means for connecting each code relay when the
corresponding contact is closed into said message
75 line circuit so as to be conditioned in accordance
with the character of the code element then
being received, a plurality of devices, and means

effective when the final code receiving relay is
conditioned for controlling said plurality of devices
provided the elements of the code received
by said code receiving relays forms a predetermined
code combination.

21. In a control system of the code type, a
stepping line circuit receiving series of time
spaced impulses, step-by-step means operated
10 through a cycle of operation by each series of
impulses on said line circuit for sequentially clos-
ing a series of contacts, a message line circuit
receiving different series of code combinations,
each series having one element for each impulse
15 on said stepping line circuit, a series of code receiv-
ing relays one for each contact of said series,
means for conditioning the first of said code relays
when the corresponding contact is closed in
accordance with the code element then being
20 received, means for conditioning the remaining
code relays when the corresponding contacts are
closed in accordance with the character of the
code elements then received only provided the
first code relay is conditioned in accordance with
25 a particular character of code element, a plurality
of devices, a means effective when the final code
receiving relay is conditioned for controlling
said plurality of devices provided the elements
of the code received by said code receiving relays
30 forms a predetermined code combination.

22. In a control system of the code type; a plurality
of stepping relay banks operable through
cycles of operation, each bank sequentially pre-
paring a series of channel circuits; means for
opening and closing said channel circuits during
35 each cycle in accordance with different code pat-
terns; a series of neutral code receiving relays,
one series for each of said stepping relay banks,
and one code relay being included in each of said
channel circuits and actuated to an energized
40 position when such channel circuit is closed;
means associated with each code relay for main-
taining it in an energized position until the end
of that cycle, whereby the particular code pat-
tern for a cycle is stored in said code relays until
45 the end of a cycle; and means selectively governed
by said code relays in accordance with the par-
ticular code pattern stored therein during
each cycle of operation.

23. In a centralized traffic controlling system
of the station selective code type, a control office
and a plurality of field stations connected by a
line circuit, code selecting relays in said office
corresponding to said stations, a manually oper-
ated lever in said office associated with each of
55 said code selecting relays, a storing relay asso-
ciated with each of said levers, a traffic control-
ling device at each of said stations, a pick-up
circuit for each of said storing relays energized
by each actuation of its associated lever, means
60 responsive to the operation of any one of said
code selecting relays for applying a character-
istic series of impulses to said line circuit for
effecting selection of a corresponding station,
means controlled by the position of the actuated
65 lever for actuating the traffic controlling device
at the selected station, means controlled by the
simultaneous operation of a plurality of said
storing relays for operating a plurality of said
code selecting relays, and means for effecting
70 only the application of a preferred series of im-
pulses when more than one of said code selecting
relays are in their operated positions at the same
time.

24. In a centralized traffic controlling system,

of the station selective code type, a control office and a plurality of field stations connected by a line circuit, code selecting relays in said office corresponding to said stations, a manually operated lever in said office associated with each of said code selecting relays, a storing relay associated with each of said levers, a traffic controlling device at each of said stations, a pick-up circuit for each of said storing relays energized by each actuation of its associated lever, means responsive to the operation of any one of said code selecting relays for applying a characteristic series of impulses to said line circuit for effecting selection of a corresponding station, means controlled by the position of the actuated lever for actuating the traffic controlling device at the selected station, means controlled by the simultaneous operation of a plurality of said storing relays for operating a plurality of said code selecting relays, means for effecting only the application of a preferred series of impulses when more than one of said code selecting relays are in their operated positions at the same time, and means for preventing the operation of any of said code selecting relays during the application of a series of impulses.

25. In a communication system of the multiple impulse type for controlling traffic controlling devices at a field station and indicating at a control office the conditions of changeable devices at such field station, a single stepping line circuit connecting said office and field station and having a series of impulses impressed thereon, a line relay at said field station connected in series in said line circuit and responsive to all the impulses of said series, a chain of neutral 10 stepping relays arranged in two groups which relays are energized sequentially in response to the operation of said line relay, a conditioning relay determining by its energization if said second group of stepping relays shall be operated following the operation of the first group, two separate relays for controlling said conditioning relay one being controlled manually from the office and the other being controlled automatically from the field when a changed indication is to 20 be transmitted, and traffic controlling relays and contacts of changeable devices to be indicated, said relays and contacts being included in partial circuits sequentially established by said second group of stepping relays. 25
